UNITED STATES PATENT OFFICE.

WILLIAM H. J. CLIFTON, OF WESTPOINT, TENNESSEE, ASSIGNOR OF ONE-HALF TO FRANK HOLLANDER, OF WESTPOINT, TENNESSEE.

RAIL-CHAIR.

No. 887,736.

Specification of Letters Patent.

Patented May 12, 1908.

Application filed September 6, 1906. Serial No. 333,494.

To all whom it may concern:

Be it known that I, WILLIAM H. J. CLIFTON, a citizen of the United States, residing at Westpoint, in the county of Lawrence, 5 State of Tennessee, have invented certain new and useful Improvements in Rail-Chairs; and I do hereby declare the following to be a full, clear, and exact description of the invention, such as will enable others skilled in the 10 art to which it appertains to make and use the same.

This invention relates to chairs for railroad rails, and more particularly to chairs including clamping devices which hold the 15 rail securely upon the chair and without the necessity of the direct engagement of spikes with the rails.

The invention to this end resides in the provision of a chair and rail clamping plates 20 which are slideable into position upon the chair to engage the rail, and which are held thereon by means of spikes which are driven through the plate, the rail engaging plates, and into the tie.

25 In the accompanying drawings—Figure 1 is a top plan view of a section of track showing my chairs in use. Fig. 2 is a similar view of one of the chairs. Fig. 3 is a view in side elevation of one of the chairs, the rail 30 therefor being shown in section. Fig. 4 is a detail vertical longitudinal sectional view through one of the chairs and a rail supported thereby, and Fig. 5 is a detail transverse sectional view on the line 5—5 of Fig. 4, the 35 rail being omitted.

Referring more specifically to the drawings, the numeral 6 denotes a railway tie, and 7 a rail, which is supported upon the tie by means of one of my chairs which will now be 40 described.

Each chair comprises a chair plate 8, which is flanged, as at 9, at its middle and along its longitudinal edges and is provided at its said edges and upon opposite sides of the flanges 45 9 with upstanding flanges 10, which are directed inwardly toward each other, as shown in Fig. 5. The rail 7 is disposed upon that portion of the chair plate which is determined by the flanges 9 and between the 50 flanges 10. The opposing end edges of the

said flanges at each side of the plate are inclined toward each other, as indicated by the numeral 11, and the distance between the end edges of the flanges at each side of the plate at the point of junction with the plate, 55 is greater than the greatest width of the base of the rail 7, to permit ready engagement of the rails with the chairs.

Rail-clamping plates 12 and 13 have their longitudinal edges beveled, as at 14, to permit them to be slid into position upon the chair plate 8 between the corresponding flanges 10 at each side of the said chair plate and inwardly and outwardly respectively of the rails with which they are engaged, and 60 upon each plate 12 and 13 at its inner end is formed an upstanding rail-engaging boss 15, the boss upon the plate 12 being of less height than the boss upon the plate 13, to permit passage of the car wheel flanges. The 65 rail-engaging faces of the bosses 15 conform to the contour of the rail, as will be readily understood, and registering apertures 16 are formed in the chair plate 8 and the rail-clamping plates 12 and 13 for the passage of 70 spikes 17, which are driven into the tie 6 and serve to hold the plates 12 and 13 in engagement with the rails and against displacement from the plate 8.

75 What is claimed, is—

A device of the class described comprising a chair plate formed with a broadened rail-supporting intermediate portion and at its longitudinal edges and at each side of the said portion with upstanding opposed flanges, rail-engaging plates seated upon the chair plate and removably received at their edges between the flanges, said plates being formed each with an upstanding rail-engaging boss which is engaged at its sides by the opposed 85 edges of the corresponding flanges upon the chair plate, and fastening devices for securing the rail-engaging plate upon the chair plate substantially as described.

80 In testimony whereof, I affix my signature, 95 in presence of two witnesses.

WILLIAM H. J. CLIFTON.

Witnesses:

J. G. DAVIS,

W. D. INMAN.
